UNITED STATES PATENT OFFICE.

T. G. MASSIE, OF PORT HENRY, NEW YORK.

IMPROVEMENT IN ROTARY STEAM-ENGINES.

Specification forming part of Letters Patent No. 44,330, dated September 20, 1864.

To all whom it may concern:

Be it known that I, T. G. MASSIE, of Port Henry, in the county of Essex and State of New York, have invented a new and Improved Rotary Engine; and I do hereby declare that the following is a full, clear, and exact description thereof, which will enable others skilled in the art to make and use the same, reference being had to the accompanying drawings, forming part of this specification, in which—

Figure 1 represents a transverse vertical section of the cylinder and piston-wheel and a longitudinal section of the piston, taken in the plane of section indicated by the line $z z$, Fig. 2. Fig. 2 is a sectional front elevation of the same, the plane of section being indicated by the line $y y$, Fig. 1. Fig. 3 is a horizontal section of the same, the line $x x$, Fig. 1, indicating the plane of section. Fig. 4 is an inside view of one section of the cylinder detached.

Similar letters of reference indicate like parts.

This invention consists in the application of cams to the inner surfaces of the cylinder-head, or in giving to said inner surfaces the form of cams in such a manner that by the action of said cams the transversely sliding piston is moved forward and backward in the guide-slot in the piston-wheel, and the steam is made to act alternately on one or on the other end of the piston or simultaneously on both ends of the same, and thereby a rotary motion is imparted to the piston-wheel.

The invention consists, further, in the arrangement of cavities in the sides of the sliding piston in such a manner that the steam is allowed to pass through said piston from one side of the piston-wheel to the other; also, in the arrangement of roller frames in the sides of the guide-slot in the piston-wheel in such a manner that the motion of the piston is facilitated and the friction reduced; further, in the arrangement of spring-abutments on the highest parts or apexes of the cams on the inner surfaces of the cylinder-heads in such a manner that by the action of these spring-abutments a steam-tight joint is effected on each side of the piston-wheel, and the passage of steam from one side of the piston to the other is prevented; finally, in movable slats inserted into the edges of the piston and exposed to the action of tri-

angular wedges, which are forced out by the action of a spring or springs in such a manner that the edges of the piston work steam-tight and with a yielding pressure against the ends of the guide-slot and against the cylinder-heads.

A represents the cylinder, which is made of cast-iron or other suitable material, and provided with a foot, B, to be secured down upon the foundation or standard C. This cylinder is bored out to receive the piston-wheel D, which fits steam tight against the bosses a in the center and against the shoulders b near the circumference of said cylinder, the joints being rendered tight by steam packing-rings $a' b'$, attached to the piston-wheel. The inner surfaces of the cylinder-heads form cams $c c'$, which rise in opposite direction, the apex of one cam being on top when the apex of the other cam is at the bottom, or vice versa. The cams $c c'$ determine the position of the piston E, which is fitted in a guide-slot, d , in the piston-wheel, and moves transversely through the same.

In order to facilitate the motion of the piston in its guide-slot, roller-frames F are inserted in the sides of the guide-slot, and by the rollers the friction of the piston in said slot is reduced. The roller-frames may be made movable, and access can be had to them through doors f^* in the cylinder-heads, so that the same and also the piston can be repaired whenever it becomes requisite. The edges of the piston fit against the ends of the slot d and against the inner surfaces of the cylinder-heads or cams $c c'$, and the joints at these edges are made tight by movable slats e , which are pressed outward by triangular wedges f and springs g . The arrangement of these slats, wedges, and springs is clearly shown in Fig. 1 of the drawings, and by referring to that figure it will be seen that the spring g is situated in a cavity within the body of the piston and guided by a longitudinal rod, g' . This rod also forms the guide for the elbow-levers g^2 , which connect by links g^3 with the triangular wedges f' . By this arrangement one elliptic spring is sufficient to act simultaneously upon all the wedges, and the packing-pieces or slats e are pressed out with a uniform pressure. The flat sides of the piston are hollowed out, as shown in Fig. 3 of the drawings, so that the steam which is admitted

on one side of the piston-wheel can pass through the piston to the opposite side of said wheel and act on the piston as the same projects from either or both sides of the same. The apex of each of the cams $c c'$ comes close up to one of the sides of the piston-wheel, as clearly shown in Fig. 3 of the drawings, and in order to produce a steam-tight joint between said apexes and the piston-wheel, packing-pieces $h h'$ are inserted, as clearly shown in Figs. 1 and 3 of the drawings. These packing-pieces are pressed against the sides of the piston-wheel by springs h^* , and they, together with the apexes of the cams, produce the requisite abutments in either section of the cylinder to enable the steam to act upon the piston. The cylinder takes steam through the pipe i and port k , and it exhausts through the port k' and pipe i' , and the ports $k k'$ are situated on the opposite sides of the apex of the cam c in that section of the cylinder in which said ports are situated. (See Fig. 4.) The steam-port is closed by a stop-valve, l , which is operated by a hand-lever, l' , and it is cut off during a short term of the revolution of the piston-wheel by the action of a slide-valve, m , to which motion is imparted by the eccentric m' , or in any other suitable manner. The piston-wheel D is mounted on a shaft, G , which passes through suitable boxes in the cylinder-heads, and has its bearings in standards H , or in the cylinder-heads, if desired. A fly-wheel, I , which is firmly keyed to said shaft, serves as the band-wheel to transmit the power of the engine to the working machines. From the time the piston reaches the apex c' of the cam until it passes the steam-port the steam in that compartment of the cylinder which is not in direct communication with the ports works expansively; but as soon as the piston passes the steam-port steam is

admitted, and it acts upon said piston with great advantage, on account of the cavities in the sides of the same, which allow the steam to pass through the piston-wheel, as previously explained. If desired, by giving the cut-off valve lead the steam may be cut off at any portion of the stroke and the steam worked expansively.

Having thus described my invention, I claim as new and desire to secure by Letters Patent—

1. The cams $c c'$ on the inner surfaces of the cylinder-heads, arranged in combination with the transversely-sliding piston E and piston-wheel D , constructed and operating in the manner and for the purpose substantially as herein shown and described.

2. Making the sides of the piston concave, substantially as herein specified, to allow the steam to pass through the piston-wheel and act on both sides of the piston.

3. The roller-frames F , applied in combination with the piston E , piston-wheel D , and cams $c c'$, substantially as and for the purpose herein shown and described.

4. The doors f^* in the sides of the cylinder, arranged in the manner and for the purpose set forth.

5. The spring-abutments or packing-pieces $h h'$, applied to the apexes of the cams $c c'$, in the manner and for the purpose substantially as herein specified.

6. The movable slats e , applied in the edges of the piston, in combination with wedges f and springs g , or their equivalents, constructed and operating substantially as and for the purpose set forth.

T. G. MASSIE.
